US0D1068761S

(12) **United States Design Patent** (10) **Patent No.:** **US D1,068,761 S**
(45) **Date of Patent:** ** *Apr. 1, 2025

(54) **SMARTWATCH**

(71) Applicant: **Samsung Electronics Co., Ltd.**, Suwon-si (KR)

(72) Inventors: **Minsoo Kim**, Suwon-si (KR); **Matthew Armer**, Suwon-si (KR)

(73) Assignee: **Samsung Electronics Co., Ltd.**, Suwon-si (KR)

(*) Notice: This patent is subject to a terminal disclaimer.

(**) Term: **15 Years**

(21) Appl. No.: **29/895,045**

(22) Filed: **Jun. 16, 2023**

(30) **Foreign Application Priority Data**

Dec. 19, 2022 (KR) 30-2022-0053299

(57) **CLAIM**

The ornamental design for a smartwatch, as shown and described.

DESCRIPTION

FIG. 1 is a front perspective view of a smartwatch showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depict portions of the smartwatch that form no part of the claimed design.

1 Claim, 5 Drawing Sheets
